UNITED STATES PATENT OFFICE.

FRANK SMILEY, OF BATAVIA, NEW YORK.

IMPROVEMENT IN PRUNING-SHEARS.

Specification forming part of Letters Patent No. 118,492, dated August 29, 1871.

To all whom it may concern:

Be it known that I, FRANK SMILEY, of Batavia, in the county of Genesee and State of New York, have invented a certain Improvement in Pruning-Shears, of which the following is a specification:

My invention consists of a reversible knife or cutting-blade of pruning-shears constructed with two cutting-edges, so as to enable the knife to be reversed when one of its edges becomes unserviceable.

In the accompanying drawing, Figure I is an elevation of my improved implement. Fig. II is a partly-sectional elevation in line $x x$, Fig. I.

Like letters designate like parts in each of the figures.

A is the crooked jaw, and A' the handle thereof, of ordinary construction. B is the cutter-plate bearing secured to the side of the jaw A by rivets b, so as to leave between the jaw and the cutter-plate a space in which the knife or blade works. C is the knife or cutting-blade, and C' the handle thereof. The jaw A and the knife C are pivoted together at d. The knife C is constructed with two similarly-formed cutting-edges, c c, arranged symmetrically on each side

of the center line thereof, and formed so as to correspond with the face of the crooked jaw A. e e are the bearing-surfaces of the knife at the joint d. They are so arranged with reference to the cutting-edges c c that, when either one of said bearing-surfaces is placed next to the jaw A, the corresponding cutting-edge will be in the proper position between the jaw A and the cutter-plate B to insure a clean cut. The knife C is in this manner rendered reversible. The knife C is beveled from the center line toward the cutting-edges, either on both sides or only on one side, as may be preferred.

My improved implement is capable of doing service twice as long as ordinary pruning-shears without requiring to be sharpened, and also avoids loss of time if one of the cutting-edges should suddenly become unserviceable.

I claim as my invention—

The reversible knife C of pruning-shears, constructed with two cutting-edges, c c, and bearing-surfaces e e, in combination with the jaw A, substantially as hereinbefore set forth.

Witnesses: FRANK SMILEY.
